DETACHABLE HANDLE

Alfred G. Olson, Chicago, Ill., assignor of one-half
to Paul Jahn, Chicago, Ill.

Application June 15, 1934, Serial No. 730,725

1 Claim. (Cl. 220—94)

My invention relates to detachable handles for paint containers or cans and the like and the main object is to provide in a simple and practical form, a handle which may be readily attached to or detached from any small can or container having marginal beads such as discarded food tins whereby said can may be conveniently handled and used by painters and decorators for holding small quantities of paint, etc.

Another object is to provide a handle of this kind including a pair of slidably connected jaw members hooked at their ends to engage the beads or ends of the can and spring set to normally draw the hooked ends together tight on said can, one of the jaw members carrying an open or looped handle for convenience in manipulating and holding the can when the handle is attached thereto.

With these and other objects in view the invention resides in the novel construction and arrangement of parts as hereinafter fully set forth and claimed, reference being had to the accompanying drawing wherein:

Figure 1 is a side view of my improved handle as mounted on a can, the latter being partially broken away and shown in cross section.

Figure 2 is a side view at an angle of ninety degrees to Figure 1.

Figure 3 is a top plan view.

Figure 4 is a perspective view of my handle alone.

Referring now with more particularity to the drawing my invention is shown as mounted on a conventional form of can A having the marginal annular lips or beads B and C around its upper and lower ends D and E. For use by decorators and painters who often have use for a small can to hold a small quantity of paint this can A may well be a discarded or emptied vegetable or fruit tin of the well known form.

For use on the above my handle comprises a pair of jaw members 5 and 6 made up of flat strip metal and arranged with their adjacent flat sides 7 together and held in slidable engagement by clips or ears 8 and 9, the ears 8 being bent over from the sides of the member 5 near its intended lower end and embracing the margins of the member 6 and the ears 9 being likewise bent from the margins of the member 6 near its intended upper end and embracing the side of the member 5. These members 5 and 6 may thus be slipped or moved axially apart as will be understood.

The jaw member 5, hereinafter termed the inner jaw member, is bent over at right angles at its upper end to provide a spring mounting head

or portion 10 and then is bent upward, over and downward to form a hook 11 open at its underside 12. In similar manner the outer jaw member 6 is bent over at right angles to provide a spring mounting foot or portion 13 and then is bent downward, over and upward to provide a hook 14 open at its upper side 15. A long retractile coil spring 16 is then stretched between the spring mounting portions 10 and 13 with its ends anchored thereto in any suitable manner as by hooking the ends 17 through perforations 18. This spring thus serves to normally urge the jaw members 5 and 6 together as shown in Figure 4.

A handle 19 is provided by bending the outer jaw member 6 first outward at its upper end then downward and inward as shown and then fastening the end 20 beneath the spring mounting foot 13. The strip from which the jaw 6 is formed is, of course, made sufficiently long to provide this handle and it is readily evident that the whole structure requires only three pieces for its make up.

In use the hook 11 is hooked over the upper bead 13 of the can A and the handle 19 pulled downward until the hook 14 may be engaged with the lower bead C, the two jaw members 5 and 6 being pulled apart by this action so that when released the spring 16 will hold the hooks tightly in place on the can. Of course the can must be of greater height than the distance between the hooks 11 and 14 at rest (Figure 4) and the distance between the ears 8 and 9 allows the jaw members to move apart a considerable distance to fit cans of varying heights. A reverse of the above action detaches the handle from the can. The spring mounting portions 10 and 13 provide clearance space between the can and the jaw members for the spring 16.

While I have herein set forth a certain preferred embodiment of my invention, it is understood that I may vary from the same in minor structural details, so as best to construct a practical device for the purpose intended, not departing from the spirit of the invention and within the scope of the appended claim.

I claim:

In a device of the kind described, a pair of flat, elongated jaw members slidably assembled together face to face and constituting one an inner and the other an outer jaw member, each said member having a pair of marginal, integral ears bent out over and slidably engaging the other member, for supporting the elements slidably together, the predetermined upper end of the inner jaw member being formed as a spring mounting

head and a bead engaging hook, the predetermined lower end of the outer jaw member being formed as a spring mounting head and a bead engaging hook complementary to the aforesaid 5 similar elements of the inner jaw member, the upper end of the outer jaw member being looped backwardly, down and forwardly to form a han-

dle, and secured at its extremity beneath the spring mounting foot of the outer jaw member, and a retractile spring stretched and secured between the respective spring mounting head and foot of the two jaw members.

ALFRED G. OLSON.
